(57) **CLAIM**

The ornamental design for a surgical table, as shown and described.

DESCRIPTION

FIG. 1 is a top-perspective-front-right-side view of a surgical table showing our new design

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a left-side view of the table in Trendelenburg position; and,

FIG. 8 is a rear view of the table in a lateral-tilted position. The broken lines are included for the purpose of illustrating unclaimed portions of the surgical table and form no part of the claimed design.

1 Claim, 6 Drawing Sheets
